DESIGN FOR WALL-PAPER.

SPECIFICATION forming part of Design No. 20,332, dated November 18, 1890.

Application filed September 27, 1890. Serial No. 366,391. Term of patent 3½ years.

To all whom it may concern:

Be it known that CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of a floral ornament composed of the dandelion flower, leaf, and seed-pod arranged irregularly over the surface of the paper, as represented in the accompanying photograph. The 15 base or body of the ornament is formed of the leaves arranged in graceful curves, and the

flowers and seed-pods hang from the stems, which shoot upwardly from the base of the ornament. Buds of the flowers detached from the ornaments are scattered over the surface 20 of the paper between the ornaments.

The design is printed upon tinted paper of any desired color.

What I claim is—

15 The design for wall-paper herein shown and described.

Witness my hand this 13th day of September, 1890.

CHARLES BOOZE.
